UNITED STATES PATENT OFFICE.

AUGUSTE MARIE CHARLES DE CORTA, OF PANTIN, FRANCE, ASSIGNOR TO LA SOCIÉTÉ DES SAVONNERIES DES VALLIÈRES ET PRAIRIA RÉUNIES SIÈGE SOCIAL, OF PANTIN, FRANCE.

MACHINE FOR CUTTING TOILET AND LIKE SOAPS.

Application filed January 14, 1924. Serial No. 686,135.

To all whom it may concern:

Be it known that I, AUGUSTE MARIE CHARLES DE CORTA, citizen of the Republic of France, residing at Pantin, Seine, France, post-office address 63 Rue Charles Nodier, have invented certain new and useful Improvements in Machines for Cutting Toilet and like Soaps, of which the following is a specification.

- 10 The present invention has for its object to provide a continuously working machine for cutting bars of toilet and like soap such as issue from an extrusion press, into cakes or tablets having approximately the shape 15 which they are intended to receive finally in the press, said machine being extremely simple in construction, consisting of but few parts and capable of producing cakes of soap of different forms.
- 20 One construction of a machine embodying the features of the invention is shown diagrammatically by way of example in the accompanying drawings in which:

Figure 1 is a side elevation,
25 Figure 2 a plan, and

Figure 3 shows in detail the frame carrying the female member of the punching mechanism, the slideway for the soap bar and various members constituting this part 30 of the machine.

Fig. 4 is a side elevation of the plunger member of the punching mechanism, detached; and

Fig. 5 is a plan view of said member.

35 The frame of the machine A—A' is mounted on the base H and carries at A a double crank B which is mounted in bearings C and is driven by any suitable means, for instance, a pulley O operatively connected to a driving member.

The rotating crank B imparts through a connecting rod D a reciprocating movement to a rod E which slides in bearings F carried by the part A' of the frame. The rod 45 E therefore receives longitudinal movement in the direction of its own axis. To the free end of the rod E is detachably secured the male member G of the punching apparatus. This male member G comprises a

50 back or base portion preferably of the form shown in Figs. 3 and 5, provided at its upper and lower ends with sharpened, forwardly projecting lips G' adapted to cut into a bar of soap in its forward movement, said lips being outwardly curved to con-

form to the curvature of the opening in the female member hereinafter described. The base portion G is curved or concaved at its edges to facilitate removal of the cut off cake of soap therefrom, and is further provided at its lower end with a pair of prongs or grippers N which after the punching operation remove the waste pieces of soap, as will be explained hereinafter. A second frame I mounted on the base H and provided with a circular opening J arranged opposite the centre of the rod E, carries the female member K of the punching apparatus which comprises a plate or disk having an opening therein, shown herein of 60 oval form, adapted to permit the passage of the male member G therethrough. It may be pointed out that members G and K are detachable which enables tablets or cakes of 65 various shapes and dimensions to be cut on 70 the machine by the aid of several sets of 75 exchangeable cutting apparatus.

An inclined slideway or chute which may be adjusted as required is fixed to the aforesaid frame I and serves for supporting the 80 bar of soap to be cut. The bar descends owing to the inclined arrangement of the slideway by its own gravity and assumes after each punching operation by which a 85 cake has been cut off the required position relatively to the punching apparatus in which it is held by a stop M fixed to the frame I.

The operation of the machine is as follows:

The machine works continuously there being no need to start and stop the machine after each punching operation. The bar of soap is placed upon the slideway L and as the plunger G moves away from the counter part K, the bar descends and rests against the stop M. Upon the return of the member G toward the member K, the lowermost portion of the bar of soap is caught between said members and upon continued advance 95 movement of the member G its upper and lower lips G' cut into the bar of soap and sever therefrom a cake, which cake will be pushed by the member G through the opening in the female member K, whereupon an operator standing in front of the machine 100 will grasp the cut cake of soap as it emerges from the member K, the member G being, as hereinbefore stated, inwardly curved at 105 its side edges to permit the ready removal 110

of said cake of soap, which is then ready to be placed in a press or mould to receive its final shape. The cake of soap delivered by the members G and K is of the same cross sectional form as the original bar, but has its ends curved. It will be obvious that, owing to the curvature of the lips of the male member G, there will be pieces of waste soap below the opening in the female member K, which will either drop into the receptacle immediately below the stop M, or will rest on said stop. In order to prevent accumulation of such waste soap to such an extent as to interfere with the operation of the member G, the so-called grippers or prongs N are secured in the lower end of said member, whereby, when the member moves backward it will drag back any waste pieces that may be in the way. At the same time the bar of soap descends again along the slideway L and is arrested by the stop M whereupon the described operation is repeated.

If desired, the same double crank might be used for simultaneously operating a second identical machine arranged on the left hand side of the axis X—Y.

Having now particularly described and ascertained the nature of my said invention and in what manner the same is to be performed, I declare that which I claim is:—

1. A machine for cutting bars of soap into tablets or cakes, comprising a two-part punching apparatus, means for reciprocating one part toward and away from the other, and feeding means for causing the bar of soap to advance by gravity between the two parts of the punching mechanism after each punching operation.

2. A machine for cutting bars of soap into tablets or cakes, comprising a two-part punching apparatus, means for reciprocating one part toward and away from the

other, feeding means for causing the bar of soap to advance by gravity between the two parts of the punching mechanism for each punching operation and means for limiting said advancing movement.

3. A machine for cutting bars of soap into tablets or cakes, comprising a two-part punching apparatus, means for reciprocating one part toward and away from the other, feeding means for causing the bar of soap to advance by gravity between the two parts of the punching mechanism after each punching operation and grippers carried by the reciprocating part for removing the waste pieces of soap during the backward movement of said reciprocating part.

4. A machine of the class described, comprising, in combination, a fixed die member having an opening therethrough, a reciprocable plunger adapted to fit said opening, means for reciprocating said member toward and from the fixed member, an inclined slideway adapted to deliver a bar of soap adjacent to said fixed member and between it and the reciprocable member, and a stop for supporting said bar in said position.

5. A machine of the class described, comprising, in combination, a die member removably secured in operative position and provided with an opening therethrough, reciprocable means adapted to move toward and from said die and centrally disposed relative to said opening, a head removably carried by said reciprocable means and adapted to fit said opening, an inclined slideway disposed in position to deliver a bar of soap by gravity adjacent to said fixed member and between it and the head, and a stop for supporting the bar in said position.

In testimony whereof I affix my signature.
AUGUSTE MARIE CHARLES de CORTA.
